RAIL SUPPORTING AND SECURING MEANS

Levi B. Armstrong, Chicago, Ill., assignor to The Lundie Engineering Corporation, New York, N. Y., a corporation of New York

Application March 5, 1932, Serial No. 596,936

6 Claims. (Cl. 238—338)

My invention relates to rail supporting and securing means, and it has for its object the provision of a new and improved form and arrangement of parts by which a rail may be suitably secured in position on a tie. It is one of the objects of my invention to provide improved means which may be effective for holding a tie plate very securely in position on a tie so that there shall be no movement of one with respect to the other and adapted to serve also for securing the rail in position on the tie plate, but arranged so that the grip on the rail at any one point shall be comparatively much less rigid so that when a wave motion traverses the rail by reason of the movement of a car wheel therealong the slight back and forth movement takes place between the rail and the tie plate rather than between the tie plate and the tie.

It is one of the objects of my invention to provide an improved arrangement of this type in which a rail is held in position by means of a clip which is adapted to yield upwardly with the rail with respect to the tie plate without loosening the connection of the tie plate with the tie.

To this end, it is one of the objects of my invention to provide an improved clip arranged so that when the engaged portion of the rail flange is moved with respect to the tie plate so as to cause the clip to yield upwardly the major portion of any distortion of the clip takes place between the point of engagement of the clip with the tie plate and the inner end of the clip. For insuring this result, it is one of the objects of my invention to provide an improved form of clip by reason of which the major portion of the distortion of the clip is confined to its intermediate portion.

It is one of the objects of my invention to provide an improved arrangement by which a clip may be permitted to yield as required independently of any distortion of the clip itself. It is another object of my invention to provide a construction of this kind in which the pressure of the outer end of the clip on the end of the tie plate is increased rather than decreased when the inner end of the clip is swung upwardly away from the tie plate. For this purpose, it is one of my objects to provide an arrangement in which the clip is formed separately from the tie plate and separately from the spring member so that the outer end of the clip is adapted to assume a canted position with respect to said two parts so as to compress the spring and exert a constantly increasing lever pressure on the tie plate as the inner end of the clip swings upwardly.

It is one of the objects of my invention to provide an improved arrangement by which a clip of the type specified may be held in position independently of the tie plate so that the clip may be removed from operative position without disturbing the mounting of the tie plate on the tie. It is one of the objects of my invention to provide an improved arrangement of this character by which the tie plate is mounted rigidly in position on the tie without any provision for relative movement between the tie and the tie plate and by which the rail is secured yieldingly in position on the tie plate so as to permit movement of the rail on the tie plate and so as to permit removal of the rail without releasing the plate attaching means.

It is another object of my invention to improve arrangements of this type in sundry details hereinafter pointed out. The preferred means by which I have accomplished my several objects are illustrated in the drawings and are herein-after specifically described. That which I believe to be new and desire to cover by Letters Patent is set forth in the claims.

In the drawings.—
Fig. 1 is a side face view of one of the preferred forms of my improved mechanism shown in position upon a rail illustrated in cross section with the top portion broken away;

Fig. 2 is a top plan view of the parts shown in Fig. 1;

Fig. 3 is a view similar to the left hand portion of Fig. 1 but showing a modified form of construction;

Fig. 4 is a view similar to a fragmentary portion of Fig. 3 but showing a slightly modified form of clip.

Fig. 5 is a view similar to Fig. 1 but showing another modified form of devices;

Fig. 6 is a top plan view of the parts shown in Fig. 5;

Fig. 7 is a view similar to the right hand portion of Fig. 5 but illustrating a modified form of construction; and

Fig. 8 is a top plan view of the clip shown in Fig. 7.

Referring now particularly to Figs. 1 and 2, in which corresponding parts are indicated by the same reference characters, 10 indicates a tie having a tie plate 11 mounted thereon, with a rail 12 mounted on the plate between the ribs 13 engaging the outer edges of the base flange of the rail. In the construction shown in Fig. 1 the tie plate 11 is provided with a plurality of spike openings 14 therethrough at each side of the rail in spaced

relation to the edge of the flange. In two of the spike openings 14, I have mounted screw spikes 15 each of which is provided with an abutment means 16 fixedly mounted on the spike serving to act as a head for the rotation of the spike into engagement with the tie 10. In the construction illustrated bevelled washers 17 are mounted on the spikes between the abutment members 16 and the top face of the plate. The spikes 15 when turned down properly hold the tie plate 11 rigidly in position upon the tie 10.

As is clearly shown in Fig. 1, each of the spikes 15 is extended upwardly beyond the abutment means 16. Upon the upper end portions of said spikes, I have mounted clips 18 of spring metal, such clips extending into position over the top faces of the flange portions at opposite sides of the rail. Above the clips 18, I have mounted double spring washers 19 in position upon the spikes, such spring washers being normally held in compressed condition by nuts 20 secured by means of screw threads on the upper end portions of the spikes. In the construction shown, the clips 18 are mounted in diagonally disposed position with respect to each other on the plate 11.

By the use of my construction, the tie plate 11 is held at all times in rigid position with respect to the tie so as to prevent any wearing movement of one with respect to the other. When a wave motion is produced in the rail by the movement of a car wheel along the rail, the spring clips 18 are adapted to yield upwardly away from the tie plate against the resiliency of the coiled spring washers 19 and against the resiliency of the clips themselves. Such yielding movement of the clips serves to permit comparatively free movement of the wave along the rail without affecting the mounting of the tie plate upon the tie. At the same time, the clips 18 hold the rail 12 strongly in position. The clips 18 are of considerably greater cross sectional size than that of the coiled spring washers, with the result that when the inner end portions of the clips are given a slight upward movement with the rail, the major part of the distortion takes place in the coiled spring and only a very small part in the clip. By my construction, the amount of compression normally applied to the spring washers can be adjusted and controlled by an adjustment of the nuts 20 independently of the degree of pressure applied upon the tie plate by the abutment means 16. In view of the fact that the fixed abutments 16 serve by themselves as the complete vertical support for the outer ends of the clips 18, with the washers 19 pressing the clips 18 downwardly against their seats directly at the spikes 15 both inwardly and outwardly thereof, the maximum necessary compression of the washers can be kept small and the likelihood of breakage of the washers is kept down correspondingly, since the washers 19 can be made very strong for resisting the comparatively small movement of the clips. As will be readily understood, whenever it is desired the clips 18 can be removed without disturbing the connection of the tie plate with the tie. As will be readily appreciated, when the clips 18 are swung upwardly with respect to the spikes 15, the outer end portions of the clips are caused to assume a canted position between the abutment means 16 and the spring washers 19, serving thus further to compress the spring washers with the result that the downward pressure on the clips by said washers is substantially increased as the clip swing upwardly.

In the construction shown in Fig. 3, a screw spike 21 of the ordinary well known type is em-

ployed in lieu of the improved form as shown in Figs. 1 and 2. In this construction, a heavy rigid clip 22 is employed in lieu of the spring metal clips 18, such clip 22 being in the form of a forging. In the arrangement shown, the outer end of the clip 22 is tapered to have its bottom face conform to the slant of the top face of the tie plate. In the arrangement shown, the bottom face of the inner end portion of the clip conforms to the slant of the top face of the rail flange. In this construction the spring washer 19 is interposed directly between the top face of the clip and the bottom face of the head of the spike. As will be readily understood, when the clip 22 is swung upwardly into canted position between the tie plate 11 and the coiled spring 19, the spring is further compressed and the outer end of the clip applies a lever pressure downwardly upon the top face of the tie plate. That is to say, when the clip 22 yields upwardly to permit a wave movement of the rail to pass, the tie plate is pressed even more firmly against the tie than before such upward swinging movement of the clip.

In the construction shown in Fig. 4, the arrangement is the same as that shown in Fig. 3 except that a clip 22—A is shown differing slightly from the clip 22 in that the clip 22—A stands normally out of engagement with the rail flange in its position overlying the flange. It will be understood that this alternative form is presented for meeting the requirements of some roads that the rail fastening means shall be kept normally out of engagement with the rail.

In the arrangement shown in Figs. 5 and 6, clips 23 are employed formed of sheet metal provided at their outer edges with down turned flanges 24 which engage the upper face of the tie plate near its opposite ends. As is clearly shown in Fig. 6, each of the clips 23 is of substantially the same width as that of the tie plate 11, being provided with two openings for the securing spikes 25. Bevelled washers 26 are preferably employed on spikes 25 between the clips 23 and the tie plate, serving as seat members through which the pressure from the springs 19 is applied directly downwardly on the tie plate without necessary reliance on the flanges 24. Each of the clips comprises a comparatively rigid outer end portion 27 and a comparatively rigid inner end portion 28, such portions being joined by a neck portion 29 of comparatively much greater resiliency. As a result of this construction, when upward pressure is applied upon the inner end portion of one of the clips 23, the major portion of the distortion of the clip takes place in the intermediate neck portion 29. In this construction also, the resilient strength of the clip at its neck portion 29 is very considerably greater than that of the two spring washers 19 bearing on the clip.

In the construction shown in Figs. 7 and 8, the arrangement is similar to that shown in Figs. 5 and 6, except that the entire inner end portion of the clip 30 is of reduced size as compared with the outer end portion. In the arrangement shown in Fig. 7, I have shown by dotted lines the normal shape of the clip 30 before its application in operative position. It is clear from this showing that the clip 30 in its applied position presses downwardly with a considerable force upon the top face of the flange of the rail.

It will be appreciated that in the construction shown in Figs. 5, 6, 7 and 8, when the inner end portions of the clips in these constructions are swung upwardly with respect to the tie plates,

the outer end portions of the clips are caused to apply an increased downward pressure upon the tie plate, just as is above described in connection with the clip 22 of the form shown in Fig. 3.

5 When the outer end portion of the clip is swung to a canted position with respect to the securing spike, the bearing of the clip upon the tie plate is shifted very slightly toward the spike. At the same time, the point of greatest pressure between 10 the clip and the coil spring is shifted slightly whereby an increased leverage pressure is applied to the top face of the tie plate near the end of the tie plate.

By my invention I have provided a construction 15 and arrangement of attaching means which are adapted to be used with any ordinary form of double shoulder tie plate without any change other than a change in the location of the spike openings. As a result of this, the tie plates to 20 be used in my improved combination arrangement can be produced without any additional expense.

By the use of my improved construction in 25 which a single screw spike at each side of the rail serves to hold the tie plate in rigid position on the tie and to hold the clip in gripping relation to the rail, I am enabled to keep the cost of material and the expense of installation to a minimum, eliminating any necessity for additional spike means at either side of the rail.

30 While I prefer to employ the form of construction as shown in my drawings and as above described, it is to be understood that my invention is not limited to such form except so far as the claims may be so limited by the prior art, it being understood that changes might well be 35 made in the form of arrangement without departing from my invention.

I claim:—

1. In a rail supporting and securing means, 40 the combination of a tie plate adapted to rest on a tie for supporting a rail thereon and having a spike opening therethrough at one side of the rail in spaced relation to the edge of the rail flange, a spike extending through said opening 45 in the plate and into the tie, abutment means on the upper end portion of the spike, a clip loosely mounted at its outer end portion on said spike so as to be movable readily into changed angular position vertically with respect to the tie 50 plate and extending inwardly from the spike into position above the flange of the rail and resilient longitudinally whereby its inner end is moved upwardly independently of the changed angular position of its outer end portion, and a coiled 55 spring mounted on said spike between said abutment means and said clip serving normally by downward pressure on the clip to hold the clip in substantially horizontal position but adapted to yield for permitting the clip to swing upwardly 60 out of normal position with respect to the spike.

2. In a rail supporting and securing means, the combination of a tie plate adapted to rest on a tie for supporting a rail thereon and having a spike opening therethrough at one side of the rail in spaced relation to the edge of the rail, a spike extending through said opening in the plate and into the tie, abutment means fixedly mounted on said spike adapted by engagement with the upper face of the tie plate to hold the plate rigidly 65 in position, a clip mounted on said spike above said abutment means and supported by said abutment means and extending over the edge of the rail flange, and means fixedly mounted on said spike above said clip for pressing said clip

yieldingly downwardly against said abutment means and releasable independently of said abutment means for removing the clip while the tie plate is still maintained in rigidly fixed position.

3. In a rail supporting and securing means, 5 the combination of a tie plate adapted to rest on a tie for supporting a rail thereon and having a spike opening therethrough at one side of the rail in spaced relation to the edge of the rail, a spike extending through said opening in the 10 plate and into the tie, abutment means fixedly mounted on said spike adapted by engagement with the upper face of the tie plate to hold the plate rigidly in position, a clip mounted on said spike above said abutment means and supported 15 by said abutment means and extending over the edge of the rail flange, a coiled spring mounted on said spike above said clip, and other abutment means removably mounted on the upper end portion of said spike above said coiled spring adapted 20 to hold said coiled spring under tension for pressing the clip yieldingly against said first named abutment means.

4. In a rail supporting and securing means, 25 the combination of a tie plate adapted to rest on a tie for supporting a rail thereon and having a spike opening therethrough at one side of the rail in spaced relation to the edge of the rail flange, a spike extending through said opening 30 in the plate and into the tie, abutment means on the upper end portion of the spike, yielding means mounted on said spike below said abutment means, and a clip mounted on said spike between said yielding means and said tie plate so as to hold said yielding means compressed and comprising a rigid portion in engagement with the tie plate connected with the portion in engagement with the rail flange by a portion of comparatively much greater resiliency.

5. In a rail supporting and securing means, 40 the combination of a tie plate adapted to rest on a tie for supporting a rail thereon and having a plurality of spike openings therethrough at each side of the rail in spaced relation to the edge of the rail flange, spikes extending through two of 45 said openings at one side of the rail and into the tie, abutment means on the upper end portion of each of said spikes, and a clip mounted on said spikes below said abutment means and comprising a rigid outer end portion in engagement with the tie plate near the end of the plate beyond said spikes connected with the inner end portion extending over the rail flange by an intermediate 50 portion of comparatively much greater resiliency.

6. In a rail supporting and securing means, the combination of a tie plate adapted to rest on a tie for supporting a rail thereon and having a plurality of spike openings therethrough at each side of the rail in spaced relation to the edge of the rail flange, spikes extending through two of 55 said openings at one side of the rail and into the tie, abutment means on the upper end portion of each of said spikes, a clip mounted on said spikes below said abutment means and comprising a rigid outer end portion in engagement with the tie plate near the end of the plate beyond said spikes connected with the inner end portion extending over the rail flange by an intermediate portion of comparatively much greater resiliency, 60 and yielding means mounted on each of said spikes between the clip and the abutment means so as to be compressed for holding the clip yieldingly in operative position.

LEVI B. ARMSTRONG.
